UNITED STATES PATENT OFFICE

ARTHUR T. BATEMAN AND ANDREW IRVINE, OF DETROIT, MICHIGAN, ASSIGNEES TO
BOHN ALUMINUM & BRASS CORPORATION, OF DETROIT, MICHIGAN, A CORPORA-
TION OF MICHIGAN

MOLD

Application filed July 30, 1928. Serial No. 296,378.

The invention relates to molds adapted for use in forming metal articles and has been developed in casting from metal of relatively high crystallization shrinkage and low fusing point, such as aluminum or its alloys, articles having curved passages therethrough, such as vacuum cleaner nozzles. Heretofore, vacuum cleaner nozzles have been cast in sand molds and as a consequence the castings were found defective. In addition, the finishing of their external surfaces required considerable labor resulting in relatively high cost. With our invention the finishing of the external surfaces of the castings require considerably less labor. At the same time the passages in these castings may be curved as desired so that no abrupt shoulders will be present.

The invention has for another object to so construct the mold that it may be operated at sufficient speed to maintain the temperature of the mold above a predetermined point so that good castings may be produced. The invention has for further objects to so construct the mold that the core may be readily inserted and will normally remain in place when the mold sections are separated; to so construct the mold that air and gas may escape from the mold cavity, thereby allowing this cavity to be filled; and to so construct the mold that the molten metal is initially poured upon a permanent part of the mold instead of the core, thereby avoiding to as large an extent as possible carrying of impurities into the mold cavity.

With these as well as other objects in view, the invention resides in the novel features of construction and combinations and arrangements of parts as more fully hereinafter set forth.

In the drawings:—

Figure 1 is a plan view of a mold embodying the invention;

Figure 2 is a cross section on the line 2—2 of Figure 1;

Figure 3 is a rear view thereof with parts broken away.

In the present instance we have shown a mold adapted for use in forming from metal of relatively high crystallization shrinkage and relatively low fusing point, such as aluminum or its alloys, an article having a curved passage therethrough, such as a vacuum cleaner nozzle.

In detail, 1 is a stationary permanent rear section of the mold and 2 a movable permanent front section. These sections are preferably formed from metal of relatively high fusing point. The front section 2 is pivotally mounted at its lower end upon the horizontally extending aligned pins 3, which are mounted upon the rear section at the front of its lower end. The rear section 1 has permanently secured thereto the permanent insert 4 which is preferably formed of the same metal as the sections 1 and 2. The mold further has the permanent side sections or cores 5, which are preferably formed of the same metal as the sections 1 and 2 and are longitudinally slidably mounted upon the rear section 1 to extend above the insert 4. These side cores are supported and guided by means of the plates 6, which are fixedly secured to the front face of this rear section. The rear section 1, including the insert 4, the front section 2 and the side cores 5 are adapted to cooperate to form the mold cavity.

The vacuum cleaner nozzle, which is adapted to be formed in this mold cavity, has the curved body 6 and the annular flange 7 at one end thereof, the passage through this nozzle being curved with adjacent portions of the wall forming the passage merging into each other to avoid any abrupt shoulders which might interfere with the passage of air and dirt therethrough and collect dirt. The parts of the mold are so arranged that the portion of the mold cavity for forming the annular flange 7 is located at the lower end and the portion of the mold cavity for

forming the portion of the body 6, which is uppermost when the nozzle is in use is located at the lower side, by reason of which a good casting may be formed having its external surface, which in use is uppermost, presenting a uniformly colored appearance, the molten metal having had an opportunity of reaching a uniform temperature by the time it reaches the lower side of the mold cavity. The side cores extending above the insert 4 and cooperating therewith to form the upper portion of the mold cavity for forming part of the annular flange 7 and the adjacent portion of the body 6, provide for escape of air or gas which might otherwise be trapped in the flange forming portion of the mold cavity, there being sufficient clearance between these side cores and the rear section to permit the escape of air and gas therebetween.

8 is a core, commonly known as a sand core. This core has a contour such that when it is placed within the mold cavity the proper thickness of the wall of the body 6 is secured. For mounting the core 8 in place, the insert 4 is provided with the tapered axial opening 9 for engagement with the print 10 at one end of the core. The rear section 1 is provided with the elongated recess 10 at the front side of its upper portion and above the part of the rear section used in forming the mold cavity. The recess preferably extends laterally beyond both ends of the mold cavity forming portion and is engageable by the elongated print 11 at the end of the core 8 opposite the print 10. The rear section furthermore occupies a position such that when the core is inserted into place while the front section 2 is separated from the rear section 1 this core naturally remains in place so that it need not be held until the front section has been brought into contact with the rear section. By reason of the print 11 being the uppermost part of the core and also being exposed, air and gas may escape therethrough while the mold cavity is being filled with molten metal.

The rear section 1 is provided with the gate 12 and the risers 13, which are preferably located beyond opposite ends of the gate. This gate has one side closed by the print 11, but is so located and inclined that the rear section is subjected to the force of impact of the molten metal for filling the mold cavity, thereby avoiding to as great an extent as possible the washing of impurities into the mold cavity from the core.

The body 6 of the nozzle has adjacent its elongated opening or mouth 14 the elongated enlargements 15 which are in the nature of ribs extending longitudinally at the sides of the opening or mouth. In order to secure proper forming or filling out of these enlargements, we have provided in the rear and front mold sections 1 and 2, respectively, the

channels 16 and 17 in which are fixedly secured the permanent inserts 18 and 19, respectively. These inserts have the longitudinally extending grooves 20 for forming the portions of the mold cavity for making the enlargements. The lower sides of these inserts 16 and 17 are formed with the restricted passages 21 preferably in the nature of file cuts, which lead to the inner beveled corners 22 of the inserts. 23 and 24 are passages preferably formed respectively in the rear section 1 and the front section 2 for conducting air and gas which may have escaped through the passages 21 to points outside the mold. The inserts 18 and 19 are preferably formed of the same metal as the sections 1 and 2 and the insert 18 is cut away to assist in forming the gate 12 and the risers 13. It has been found that with this arrangement of inserts the molten metal will properly fill out the cavities formed by the grooves in the inserts so that the elongated enlargements are properly formed.

With the parts as thus far described and assuming the permanent sections and side cores to be heated to a temperature essential to the proper pouring of molten aluminum or its alloys and also assuming that the front section 2 has been swung forwardly and downwardly, a sand core 8 is inserted into place by placing its print 10 in the opening 9 and its print 11 in the recess 10, at which time this core will naturally remain in place and be accurately positioned. The front section 12 is then swung upwardly and rearwardly against the stationary section 1. The side cores are moved longitudinally inward to positions determined by their end flanges 25, after which the front section is suitably clamped to the rear section. The mold is now in condition to receive molten metal which is poured in through the gate 12 and passes around the core, gradually filling the mold cavity. Any air which might otherwise collect in the portion of the mold for forming the annular flange of the article is permitted to escape between the side cores and the rear section and any air which might otherwise collect in the grooves for forming the elongated enlargements at the opposite sides of the inlet opening or mouth of the article is permitted to escape between the inserts and the mold sections in which they are located. Owing to the fact that the metal which forms the uppermost part of the article when in use has had an opportunity to cool to a uniform temperature, this metal has a better appearance and does not show, at least to as large an extent, variations in color. When the molten metal has cooled sufficiently, the clamps for securing the front section 2 to the rear section 1 are released, the side cores are drawn longitudinally outward and the front section 2 is then swung

forwardly and rearwardly, after which the article may be removed.

Owing to the fact that the portion of the mold cavity forming the external surface 5 of the article is permanent and more particularly metallic, the external surface of the article has a better natural finish and does not require nearly as much labor to completely finish the same. However, since a sand core 10 is used, the passage through the article may be curved as desired with adjacent portions merging into each other, thereby avoiding abrupt shoulders.

What we claim as our invention is:

15 1. A mold adapted for use in forming a vacuum cleaner nozzle having a curved passage therethrough with adjacent portions of the wall forming the passage merging into each other and an annular flange at one end, 20 said mold comprising a stationary permanent section, a pivotal permanent section adapted to cooperate therewith to form an upright mold cavity, the permanent sections occupying a position such that the portion of the 25 mold cavity forming the annular flange of the nozzle is at the lower end of the cavity, one of said permanent sections being provided with gate means communicating with the upper end of the mold cavity and a sand 30 core carried by said stationary section and insertable into place when the permanent sections are separated.

2. A mold adapted for use in forming a flanged article comprising a stationary permanent section, a movable permanent section 35 adapted to be secured against the stationary section and side cores movably mounted upon one of the sections, said sections and cores being adapted to cooperate to form an upright 40 mold cavity with a flange forming portion at the lower end and said cores providing for escape of air and gas from the flange forming portion, one of said sections being provided with gate means communicating with the upper 45 end of the mold cavity.

3. A mold adapted for use in forming a flanged article comprising a stationary permanent section, a pivotal permanent section adapted to move through a vertical path and 50 to be secured against the stationary section and side cores longitudinally slidably mounted upon the stationary section, said sections and cores being adapted to cooperate to form an upright mold cavity with a flange forming portion at the lower end and said core providing for escape of air and gas from the flange forming portion, one of said sections being provided with gate means communicating with the upper end of the mold cavity.

60 4. A mold adapted for use in forming an article having an elongated opening at one end with an external rib extending longitudinally of and at one side of the opening, said mold comprising fixed and movable permanent sections adapted to cooperate to form

the mold cavity and a core carried by said fixed section and adapted to occupy a predetermined position in the mold cavity, one of the sections having a permanent insert grooved to form the rib and constructed to 70 provide for the escape of air and gas from the groove.

5. A mold for use in forming a vacuum cleaner nozzle having a longitudinally curved passage therethrough comprising fixed and 75 movable permanent sections cooperating to form an upright mold cavity increasing in cross-section toward its lower end, gate means communicating with the upper end of the mold cavity and a sand core adapted to occupy a predetermined position in the mold cavity and defining the longitudinally curved passage.

6. A mold for use in forming a vacuum cleaner nozzle having a longitudinally curved 80 passage therethrough comprising a stationary section, a pivotal section adapted to cooperate therewith to form an upright mold cavity increasing in cross-section toward its lower end, gate means communicating with 85 the upper end of said mold cavity and a sand core adapted to be carried by the stationary section and to occupy a predetermined position in the mold cavity and defining the longitudinally curved passage.

7. A mold adapted for use in forming a flanged article comprising a stationary permanent section, a pivotal permanent section adapted to be secured against the stationary section, and side cores movably mounted upon 100 the stationary section, said sections and cores being adapted to cooperate to form an upright mold cavity with the flange forming portion of the cavity partly formed between the stationary section and the side cores 105 mounted thereon.

8. A mold adapted for use in forming an article having an outwardly extending flange and a longitudinally curved passage therethrough comprising a stationary permanent section, a pivotal permanent section adapted to be secured against said stationary section, side cores movably mounted upon the stationary section, said sections and cores cooperating to form an upright mold cavity 110 with the flange forming portion of the cavity partly formed between the stationary section and the side cores mounted thereon, a sand core adapted to occupy a predetermined position in the mold cavity for defining the longitudinally curved passage, and cooperating means upon said core and stationary section 115 beyond the mold cavity for supporting the sand core from the stationary section.

9. A mold adapted for use in forming an article having a passage therethrough and a flange adjacent one end thereof comprising a stationary permanent section, a pivotal permanent section adapted to be secured against the permanent section, side cores longitu- 120

nally slidably mounted upon the stationary section; said sections and cores being adapted to cooperate to form an upright mold cavity with a flange forming portion at the lower end thereof, said flange forming portion being defined in part by said stationary section and by the side cores movable thereon, and a temporary core carried by said stationary section and occupying a predetermined position in the mold cavity for forming the curved passage.

In testimony whereof we affix our signatures.
